No. 758,674.

PATENTED MAY 3, 1904.

G. E. MELLEN.
TOY PROJECTOR.
APPLICATION FILED SEPT. 19, 1903.

NO MODEL.

UNITED STATES PATENT OFFICE.

GEORGE E. MELLEN, OF CHICAGO, ILLINOIS.

TOY-PROJECTOR.

SPECIFICATION forming part of Letters Patent No. 758,674, dated May 3, 1904.

Application filed September 19, 1903. Serial No. 173,891. (No model.)

To all whom it may concern:

Be it known that I, GEORGE E. MELLEN, of Chicago, in the county of Cook and State of Illinois, have invented a new and useful Improvement Toy-Projector, of which the following is a full, clear, and exact description, reference being had to the accompanying drawings, forming a part of this specification, in which corresponding letters of reference in the different figures indicate like parts.

My invention relates to children's toys, and has for its object to provide a simple and satisfactory means for projecting toy-like elements adapted to be actuated by a single impulse—such, for example, as an arrow, a top, or other article having a right-line or rotary movement, either singly or together; and my invention consists in the combination of elements hereinafter more particularly described, and definitely pointed out in the claims.

In the drawings, Figure 1 is a perspective view of my improved projector, showing in connection therewith three articles—viz., a winged spiral, an arrow, and a top—all substantially as they would appear when being projected from said device. Fig. 2 is a longitudinal sectional view thereof taken upon the line 2, Fig. 1, viewed in the direction of the arrow there shown. Fig. 3 is a longitudinal sectional view taken upon the line 3, Fig. 1, viewed in the direction of the arrow there shown. Fig. 4 is a transverse sectional view in plan taken upon the line 4, Fig. 3; and Fig. 5 is a view in perspective of the lower end of the inner cylinder, showing means thereon for detachably connecting a top therewith.

Referring to the drawings, *a* represents an oblong hollow case, preferably rectangular, or substantially so, in cross-section, within which is inserted a hollow cylinder *b*, the outer diameter of which is less than that of the hollow chamber *c*, formed within the case *a*. Within the hollow cylinder *b* in turn is placed a shaft *d* of such a size as to leave an annular space *e* between it and the interior of the cylinder *b*. The latter cylinder is partially closed at one end, as shown at *f*, Fig. 3, and centrally bored to fit the shaft *d*, which is longer

than the case *a* and is journaled therein at one end, as shown at *g*, Figs. 2 and 3. Into an enlarged bore in the opposite end of the case *a* is fitted a circular plug *h*, which rests against a shoulder, as shown, and is adjustably secured therein by means of two or more screws *i*, Figs. 1 and 4, which enter a groove *j* upon the periphery of said plug, the points of said screws projecting slightly into the wood at the bottom of said groove, as shown. One end of the cylinder *b* is loosely journaled in a recess *k*, Figs. 2 and 3, formed in the plug *h*, while the end of the shaft *d* is likewise journaled in a bore *l*, formed in and concentric with said plug. A spiral spring *m*, Figs. 3 and 4, is arranged to surround the shaft *d*, one end of which is rigidly secured to the cylinder *b*, as shown at *n*, Fig. 3, while the other end is attached to the plug *h*, as shown at *o*, Figs. 3 and 4.

A longitudinal slot *p*, Figs. 1 and 2, is formed in the casing *a*, which slot is substantially tangential to the periphery of the cylinder *b*. Pins *q* *q*, preferably about an inch apart, are inserted through said slot, as shown, to form stops for a cord *r*, which is projected through said slot, as shown, the respective ends of said cord being permanently attached to the cylinder *b* near its opposite ends by means of tacks *s* *s*, Fig. 2.

In assembling the device the shaft *d* is first placed within the cylinder *b*, and the plug *h* is mounted upon the end of said shaft with the spring *m* secured in place, as described. The ends of the cord are then projected through the slot *p*, so as to pass around the pins *q*, as shown in Fig. 2. The cord being fully wound upon the cylinder, the plug *h* is then rotated against the pull of the cord until the desired tension is imparted to the spring, when the plug is secured rigidly in place by means of the screws *i*.

A transverse notch *t* is formed in the casing *a* between the pins *q*, and a notch *u*, Figs. 1 and 2, is preferably cut downwardly in said case to permit the loop of the cord to be readily grasped by the fingers. Inasmuch as the cord is arranged to act against the tension of the spring, it follows that the withdrawal or unwinding and subsequent release of the

cord will cause it to be suddenly rewound by the force of the spring. Any projectile, therefore, such as an arrow v in Fig. 1, may be propelled by the recoil of the spring the same as 5 if it shot from a bow.

Upon one end of the shaft d , which is rigidly connected with the cylinder b , so as to rotate therewith, is secured a metal plate or ferrule having two raised and oppositely-projecting lugs w upon its face, which are adapted to enter slots w' in a spirally-winged projectile x . A central pin w'' is also formed upon said plate, adapted to enter a bore w^3 in the part x . When the case a is held in a vertical 15 position, as shown in Fig. 1, and the winged projectile is placed loosely upon said lugs and central pin, the manipulation of the cord r will serve to rotate the shaft d and project the part x upwardly into the air with a whirling motion. The opposite end of the shaft is provided with a central bore y , Figs. 3, 4, and 5, and is cut away at y' , while curved fingers y^2 are attached to the end of the part d with their free ends extending over the cut-away 20 portions y' , as clearly shown at Fig. 5. A top z , Fig. 1, is provided with the usual stem z' , adapted to fit loosely within the bore y . A pin z'' is projected through the base of said stem in such a way that when the stem is inserted within the bore y and slightly rotated 25 toward the left hand the fingers y^2 will engage the projecting ends of said pin and hold the top in connection with the part b . A sudden reverse movement of the shaft d while in a vertical position, as shown, will serve not only 30 to impart a rotary motion to the top z , but to disengage the fingers y^2 from the pin z'' and permit the top to fall to the ground without impeding its rotary motion.

It will be seen from the foregoing that by placing the case a in the position shown in Fig. 1, connecting the part x upon the pins w , the arrow v against the cord r , and the top z in connection with the fingers y^2 , and then 35 unwinding and releasing the cord, the winged device x , the arrow, and the top will each be projected, so as to impart the requisite motion to them respectively, or the same movement may be imparted to each successively.

Having thus described my invention, I claim—

1. The combination in a toy-projector of a

case forming a handle, a revoluble spring-controlled cylinder mounted therein, a cord wound upon said cylinder in opposition to said spring, both ends of said cord being attached to said cylinder while the loop is carried through an opening in the case and means for retaining the loop upon the outside of the case. 55

2. The combination in a toy-projector, of a case, a shaft mounted therein, a hollow cylinder surrounding said case to rotate therewith, a coiled spring having one end connected with said case and the other with said cylinder, a cord wound upon said cylinder in opposition to said spring, the middle or loop of said cord being carried through an opening in said case, and means for permanently retaining said loop upon the outside of said case. 60

3. The combination in a toy-projector, of a case adapted to form a handle, a revoluble spring-controlled cylinder mounted therein, the shaft of said cylinder being arranged to project from said case, a cord having its opposite ends attached to the periphery of said cylinder at or near the ends thereof respectively, means for maintaining the loop of the cord upon the outside of the case and means upon an end of said shaft for detachably connecting a toy to be projected by the recoil of 75 the spring. 80

4. The combination in a toy-projector of a case adapted to form a handle, a revoluble spring-controlled cylinder mounted therein, the shaft of which projects from the ends of 85 the case, a cord having its opposite ends attached to the periphery of said cylinder at points separated from each other a predetermined distance while the loop is extended through an opening to the outside of the case, 90 pins separated from each other to form a stop for said loop, a notch formed in said case opposite said loop, and means upon the ends of said shaft for detachably connecting toys thereto, whereby a plurality of toys may be 95 projected in different directions by the recoil of the spring.

In testimony whereof I have signed this specification, in the presence of two subscribing witnesses, this 17th day of September, 1903. 100

GEORGE E. MELLEN.
